NONREFILLABLE BOTTLE

Arthur E. Read, Bronx, N. Y.

Application November 30, 1934, Serial No. 755,319

14 Claims. (Cl. 215—21)

This invention relates to nonrefillable bottles and more particularly to the top portion or neck part thereof by means of which liquid may be readily poured out of the bottle in order to permit of the discharge of its contents whereas refilling of the bottle after the same is empty is rendered impossible.

So-called nonrefillable bottles have long been known and a great number of them have been placed on the market, but as a matter of actual demonstration, relatively few are nonrefillable only in name and can be readily refilled through the employment of appropriate apparatus generally utilizing a partial vacuum.

15 The devices of the prior art have in the main consisted in floats or buoyant bodies of cork and the like and weights which were operated upon solely by gravity for the purpose of closing outlet orifices in the event that it was attempted to 20 refill the bottles with which they were associated. Other and more successful devices from the standpoint of actual safeguard, have consisted in the use of springs and other similar adjuncts, but such devices and particularly metallic parts 25 are undesirable because of possible corrosion and failure to operate. The ultimate result is that, after exhaustive consideration of the prior art and prior practice, the past production of a truly nonrefillable bottle is not only questionable, but relatively remote.

It should be borne in mind in this connection that in order to be practical and meet the common need, a structure of the character described must be relatively cheap to manufacture. It 35 must embody relatively few parts and it must be sufficiently economical to make and attach to allow the same to be associated with a bottle without materially adding to the cost of the ultimate product. This question of cost has apparently 40 constituted an insurmountable barrier against the production of nonrefillable bottles on a commercial scale, so that of all the bottles heretofore known and of which I am aware, there is but one which has apparently proven commercially nonrefillable and that is one which embodies a metal spring.

With the foregoing considerations in mind, the object of the present invention is to provide a bottle which will be absolutely nonrefillable, one 50 which can be manufactured and incorporated in bottle construction at a price which is in nowise prohibitive, one which will embody a minimum number of working parts, one which will be devoid of metallic parts to come in contact with 55 the contents of the bottle; one which will pour

easily and with sufficient rapidity to meet dispensing requirements; and one which, if an attempt is made to refill the same through the use of a vacuum, will cause the parts to be locked in such manner that it can not be refilled, but will trap 5 any liquid which may remain in the bottle in such an effectual manner that it will be necessary to break the bottle to remove the remaining contents.

The present invention is characterized by a principle peculiarly novel to this art in that it 10 utilizes certain physical phenomena incident to presence of liquid under a hydrostatic head and which hydrostatic head, in accordance with the method forming part of this invention, serves to act upon a nonbuoyant sealing element to cause 15 the same to be shifted toward and away from an appropriate seat in a manner to permit dispensing of the liquid when desired, but to positively preclude refilling of the bottle either under conditions of pressure or partial vacuum.

The principle to which I have referred is utilized by the present invention to act upon a nonbuoyant body confined within a walled guide which may be graphically referred to as a guide tube or cage which serves as a guide for said body 25 and is shaped to conform substantially with the cross sectional shape of the body, the body and its guide tube being so proportioned as to provide clearance between them to permit of the movement of said body. Said clearance is, however, relatively slight, so as not to permit of appreciable by-passing of the liquid about the body. As a result, the application of pressure, hydrostatic or otherwise, against the body in a direction longitudinally of the guide tube will be 30 directed against one side of the body and since it cannot pass the body will act thereon to shift the body axially of the tube into and out of co-operative relation with the seat associated therewith. In conjunction with the body and its guide tube, there is utilized what may be termed a diverting element or flow controlling element, operating as a check valve, and preferably buoyant and the function of which is to so control 35 the flow of liquid or gaseous pressure as to direct 40 it against the non-buoyant body when an attempt is made to refill the bottle, to the end that the non-buoyant body may be thus acted upon by pressure, hydrostatic or otherwise, to firmly engage with its seat and thus preclude entry of 45 liquid into the bottle.

Basing the invention on these novel principles, the structure is as hereinafter more fully described in detail to function in a manner specified 55 in order to permit a ready flow of liquid from the

bottle for dispensing purposes and to preclude the re-entry of the liquid into the bottle.

Features of the invention, other than those specified, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figures 1, 2, 3, and 4 are diagrammatic views illustrating the method of this invention.

Figure 5 is a vertical central section through a bottle equipped with the device of the present invention.

Figure 6 shows illustrative parts of the present invention illustrated in Figure 5 dismantled.

Figure 7 is a view similar to Figure 5, but illustrates the position of the parts for dispensing liquid from the bottle.

Figure 8 shows the manner in which the production of a partial vacuum within the bottle incident to an attempt to refill the same will cause the bottle to become substantially permanently sealed.

Figures 9-12 are more or less diagrammatic sections showing different operations which take place in the device when an attempt is made to refill the same.

Figure 13 shows a central section of a slightly modified form of construction.

In Figures 1-4, I have illustrated the method of this invention in a diagrammatic manner. I have therein shown the way in which the non-buoyant sealing member functions under the application of pressure to move toward and away from a valve seat. By reference to these figures, 1 indicates a non-buoyant body shown for the purpose of present illustration as spherical. This body is positioned within a cylindrical walled passage 2 provided adjacent one end with a valve seat 3 and having a suitable stop or abutment 4 at its other end. Both the body 1 and the passage 2 are of the same cross section, for example, circular, and are of substantially the same diameter although the body 1 is slightly smaller in order to give appropriate clearance. This clearance, however, should not be great, but there should be on the contrary a relatively close fit so that liquid flowing through the passage and engaging the sphere 1 will not freely flow about the same, but rather will be substantially precluded from flow through the passage by said sphere. Slight leakage, however, between the sphere and the wall of the passage is not serious, but the fit should be sufficiently close, so that there can be no real flow between these parts through the clearance space.

60 The sphere 1 should be of greater specific gravity than the liquid with which it is used, so as to be non-buoyant as stated. It is preferably of glass, porcelain, "bakelite", or any other suitable material which is hard and unyielding, so as to preserve its shape indefinitely, and this material should be such that it is not acted upon by the liquid associated therewith in a way to change its size or in a manner to color or flavor the liquid.

70 Around at least a portion of the length of the passage 2 beyond valve seat 3 is a by-pass 5, the outlet end of which is provided with an appropriate check valve 6 which may partake of a wide variety of forms, an example of which will be hereinafter more fully explained with reference 75 to the structure. Irrespective of its structure,

the check valve should be such as to permit the passage of liquid through the by-pass 5 and in the direction of the check valve, but to seal said passage against retrograde flow of the liquid.

Now, with reference to Figure 1, it will be noted that when this arrangement of primary elements is positioned horizontally, as shown, the column of liquid 7 under an appropriate hydrostatic head and directed into the passage 2 from the valve seat end 3 thereof will act upon the non-buoyant element 1 with sufficient force to impel said element away from the seat 3 and in the direction of the stop 4, as shown in Figure 1, to thereby uncover the by-pass 5, so that after the liquid has forced the body 1 beyond the by-pass and against the stop 4, the liquid pressure will hold the body 1 in this position, while a portion of the liquid will be diverted through the by-pass 5, unseat the check valve 6 and may be discharged therethrough. There may be a slight amount of leakage of the liquid through the clearance space around the body 1, but this is inconsequential and unimportant. An important feature is that liquid will be discharged through the check valve 6.

10 A further important factor of this invention is that the body 1 while non-buoyant in character should be such that hydrostatic pressure of the liquid column 7 will shift the sphere 1 as stated when applied thereto as shown in Figure 1.

15 In view of what has been said, it will be noted that if the column of liquid 7, instead of being directed into the valve seat end of the passage 2, is directed into the passage from the opposite end thereof, so as to pass the stop 4 and flow into the passage, a directly contrary result will occur. That is to say, the check valve 6 will be seated and the pressure of the liquid column will be directed against the sphere 1 to move it to the left in Figure 1 and into engagement with the seat 3. As a result, the flow of liquid through the passage 2 in such counter direction will be absolutely precluded by a forceful seating of the sphere 1 on the valve seat 3. Thus the part 1 is shifted by hydrostatic pressure in either direction depending upon the direction of directed flow of the liquid column 40 due primarily to the relatively slight clearance and the ability of the hydrostatic pressure to move the sphere longitudinally of the passage as stated. It may be also noted in this regard that 45 pneumatic pressure will act upon the sphere 1 in the same way.

50 I have hereinbefore referred to the operation of the parts when occupying a horizontal position. In Figure 2, I have shown said parts in a vertical position. In this figure, the parts are shown inverted with the valve seat at the top and here the liquid column 7 will be assisted by gravity in impelling the sphere away from its seat and against the stop 4, the liquid thereupon being dispensed through the by-pass 5 and 55 through the check valve 6. In Figure 3, the parts are shown in vertical upright position with the valve seat 3 at the bottom. Here the column of liquid 7 will be assisted by gravity in forcing the sphere 1 into engagement with the valve seat to preclude flow of liquid through the passage.

60 In Figure 4, the same general inverted arrangement is shown as in Figure 2 with the valve seat 3 at the top. The liquid column 7 moving upwardly will lift the sphere 1 and cause it to engage with the seat 3, thus sealing the passage and overcoming the force of gravity in its operation.

65 It will thus be seen that the operations of the sphere 1 are not dependent upon gravity nor 70

buoyancy, but rather upon differential pressures, the sphere being moved in the direction away from the greater pressure.

The foregoing method steps are carried out 5 in the apparatus of this invention in a manner next to be described. In Figures 5-12 of the drawings, 8 designates the neck of a container shown as a bottle. This bottle may be of any capacity and of any desired shape and the apparatus forming part of this invention may be incorporated either in whole or in part directly in the neck of the bottle or in a separate assembly adapted to be permanently attached to the bottle neck. I have chosen the latter construction in 10 15 the interest of economy in manufacturing and packaging liquids. To this end, I employ a housing 9 adapted to be permanently secured to the bottle neck 8 after the bottle has been filled, by spinning a ring 10 in place to form a union between the parts.

In assembling these parts, I preferably insert 20 between the housing 9 and the neck 8 an apertured disk 3 so proportioned as to extend between the housing and the neck to form a gasket to 25 preclude leakage in this joint. The center of the gasket is cut away as shown at 11 to form an outlet for liquid and a sphere 1 is adapted to cooperate with this gasket, the latter serving as a valve seat for the sphere 1 which thus constitutes a sealing member. I find this structure 30 highly practical particularly when the part 3 is formed of yieldable material such as rubber or cork as it thus performs the function of a combined gasket and valve seat and provides for a 35 very efficient seal against the flow of liquid into the bottle. However, I do not limit the invention to the incorporation of this element as the sealing element 1 may, if desired, seat directly in the mouth of the bottle or upon a separate 40 seat member either of yielding or non-yielding material mounted at the neck of the bottle. The advantage of the yielding seat, however, is that little care need be exercised in making the bottle and the bottle necks may vary within considerable 45 limits in size and shape without interfering with the operations of the device.

The sealing element 1 is confined within a passage 2 formed within a guide 12. This guide may differ within wide limits from a structural 50 standpoint, but it should in any event provide the walled passage 2 extending longitudinally of the device and should be provided further with a by-pass 5 leading from the vicinity of and beyond the valve seat to a point beyond the outermost travel of the sphere 1 and there provided 55 with a check valve 6. For economy in manufacture and convenience in assembly, this guide member 12 is shown in the form of a cage comprising concentric cylindrical walls 13 and 14 and shown in detail in Figure 6, these walls being spaced apart by ribs 15 to maintain them rigidly in position. The outer diameter of the wall 13 is of a size to closely fit within the interior bore of the housing 9 and to seat at its lower edge upon the gasket 3. The space between the inner and outer walls constitutes the by-pass 5 which is thus made of very considerable cross sectional area in order to permit of rapid discharge of liquid therethrough. Stop 4 is preferably 60 made in the form of an abutment cast integral with the housing 9 and has formed therewith a baffle 16 underlying the discharge outlet 17 of the housing so that the interior structure may not be tampered with by the introduction 65 of wires or other devices.

The baffle 16 and stop 4 are properly spaced from and mounted on the housing by integral ribs 18 as shown. The check valve 6 is shown in the construction of Figures 5-12 in the form of an annulus of buoyant material, such as a flat cork ring, the same being confined within the housing above the cage 12. The cork ring is of preferably slightly less outer diameter than the interior diameter of the housing and is guided for axial movement by ribs 19 which serve to reduce friction between the ring and the housing. 5 10

It may here be noted that the use of a sphere 1 as a unit member is also intended to reduce friction incident to the movement of the sealing member in the passage 2 and that if desired the sealing member may be of other shapes appropriate to function as a valve sealing member when cooperating with an appropriate seat. In any event, it should embody appropriate mass and be of non-buoyant material as described in connection with the sphere shown. 15 20

The parts are manufactured as illustrated in Figure 6 and are assembled as shown in Figure 5. In practice, the container is filled with liquid prior to the assembly of the non-refillable device thereon, but such assembly may be carried out with neatness and dispatch as it embodies only two moving parts. 25

After the bottle has been filled and the housing and its adjuncts are secured in place thereon, the liquid is packaged and ready for the market. If desired, however, and by preference, a screw cap or other appropriate closure is associated with threads 20 formed on the exterior of the housing, so as to keep out dirt and preclude spilling of the contents if the bottle is tilted. When it is desired to dispense liquid from the bottle, the closure associated with the threads 20 is removed and the bottle tilted as shown in Figure 7. This tilting will cause the hydrostatic head of the liquid contained in the bottle to be directed against the sealing element 1 with the result that the hydrostatic head will cause the element 1 to move away from the seat 3 and into engagement with the stop 4. Gravity will of course assist in this movement of the sealing element, but it is not essential as the hydrostatic pressure will be more than sufficient to produce this result. As the element 1 leaves its seat, it uncovers the by-pass 5, so that a portion of the liquid is diverted and flows through the by-pass. The pressure of such liquid forces the check valve 6 from its seat and against shoulders 21 formed on the ribs 18, so that the contents of the bottle may be discharged through the by-pass and through the central opening in the ring 6, thence between the ribs 18 and through the outlet 17 of the housing. The path of the liquid is shown in Figure 7 by the full line arrows. Simultaneously air may enter into the bottle as indicated by the dotted line arrows, so as to displace the liquid poured from the bottle. 30 35 40 45 50 55 60

Practice has demonstrated that the bottle will pour quickly and without that slow "dribbling" effect which has long constituted a disadvantage in non-refillable bottles as heretofore constructed. With the present invention air freely enters the bottle in the manner shown allowing the liquid to readily flow therefrom. 65

When a sufficient quantity of the contents has been dispensed as stated, the bottle is returned to upright position and immediately the sealing element 1 will fall by gravity to its seat and the ring 21 will similarly descend to its seat. 70

The operations described may be repeated until 75

the bottle is empty and thereafter the bottle should be destroyed in accordance with the practice dictated by the use of non-refillable bottles.

However, should an attempt be made to refill this bottle, the following operations of the various parts will take place.

The more common method of unlawfully and surreptitiously refilling bottles is to invert the bottle, as shown in Figure 9, in an appropriate closed vessel to which a partial vacuum may be imparted. When the bottle of this invention is thus housed, the sealing element 1 and check valve 6 will fall by gravity into the positions shown in Figure 9. The next step usually employed is to exhaust the air from the vessel with the result that a partial vacuum is produced within the vessel and within the bottle. This having been accomplished, the mechanism for producing the partial vacuum is disconnected and liquid is permitted to flow into the vessel. Figure 9 shows the liquid lever rising, said liquid being indicated by the reference character 22. The liquid will rise in the vessel until it passes into the housing 9 and contacts with the ring 6. Being buoyant, this ring will thereafter rise with the liquid until it seats at the outlet of the by-pass 5, as shown in Figure 10 and even though it did not respond to buoyancy instantly, the flow of liquid into the vessel is sufficiently rapid, so that the flow of liquid into the housing 9 acts as a hydraulic piston. This is augmented by the fact that the cross sectional area of the housing and neck of the bottle is materially less than the internal cross sectional area of the body of the bottle and consequently as the liquid rises to and starts to enter the housing it does so with a rush. Consequently, the check valve 6 will be driven to its seat under considerable force and with great rapidity. This operation is further due to the fact that the liquid in passing about the baffle 16 is directed against the under face of the ring 6 and must change direction in order to flow into the passage 2. During this change of direction considerable amount of force of the liquid will be directed against the under face of the ring for the purpose of shifting the same into seated position as shown in Figure 10. The seating of this ring constitutes a seating of a check valve, thus precluding flow of liquid through the by-pass 5, and there results a differential pressure on opposite sides of the sphere 1. In other words, there is a partial vacuum in the bottle and a hydrostatic head against the opposite side of the sphere. As a result, the sphere rises under the hydrostatic head, as shown in Figure 11, and engages with its seat 3 as therein illustrated.

If liquid continues to flow into the filling vessel, the hydrostatic head will increase or if the vessel is vented, the air pressure therein will become atmospheric thereby producing a very marked pressure differential between the interior of the bottle and the exterior thereof with the result that in the specific structure described with a yielding valve seat 3, the sphere 1 will be forced with great pressure against its valve seat causing the same to be deformed, as shown in Figure 12. If the bottle is now removed from the vessel, it will be found that the engagement of the element 1 with the seat 3 has become so tight as to seal a partial vacuum within the bottle and make this seal practically permanent, at least for very prolonged periods. In other words, if an attempt is made to refill the bottle of this invention in the manner described, it will result in producing a substantially permanent seal to the bottle which can

only be destroyed by a breaking of the bottle or removing the ring 10 which, for practical purposes, is equivalent to destroying the bottle.

I have described refilling of the bottle in inverted position. Substantially the same operations will result if an attempt is made to refill the bottle in a horizontal position for the method of the invention as described in connection with Figure 1 will be carried out and the sphere 1 will be seated. It is possible, however, that if the bottle is positioned horizontally while attempt is made to refill the same, that the check valve may not operate immediately by gravity, but it will be shifted by the flow of liquid thereagainst as stated and the sphere will be forced immediately to its seat.

If an attempt is made to fill the bottle in vertical position, the sphere will drop to its seat of gravity and it will be impossible to introduce liquid into the bottle.

I have referred to the use of a disk 6 of buoyant material as a check valve and I prefer this construction in the interest of economy as this ring may be made of cork. It is possible, however, to employ a non-buoyant ring for this purpose or any other suitable form of check valve, spring operated or otherwise, without departing from this invention. If a non-buoyant ring is employed, it should, however, be of relatively light material so as to act immediately when a column of liquid engages it and to be forced thereby to the seat. It will of course be understood in this connection that it is not essential that this ring remain seated for any appreciable length of time, as the sphere 1, when once engaged with its seat 3, will remain seated by the vacuum in the bottle and even though the check valve opens the liquid cannot pass its seal.

In Figure 13, I have shown a slightly modified form of construction. This structure embodies all of the elements hereinbefore described in conjunction with the previous figures, but in addition thereto I position a non-buoyant ring 23 above the buoyant ring 6. These two rings are made separate and unattached to one another and the purpose of this non-buoyant ring 23 is to overcome the buoyancy of the ring 6 when the bottle is in upright position. The structures are otherwise the same.

In the mode of operation of this invention, the structure may be graphically referred to as having the analogy of a piston and cylinder. For example, the cylindrical walled passage 2 may be said to correspond to a cylinder in which the sealing element 1 functions after the manner of a piston with a sufficiently close fit to preclude serious leakage, the piston serving also as a sealing member of a valve, so that when moved in one direction, it engages with the valve seat, while when moved in the other direction, it engages with the stop 4. This stop 4 may be made separate from the cylinder as shown, or the outer end of the cylinder may be constricted or otherwise formed to serve as a stop or lugs may be formed therein for this purpose. The by-pass 5 in its analogy serves to by-pass the whole or a portion of the length of the cylinder, but in any event, it by-passes the valve sealing member 1 when the latter is free from its seat. The piston while mechanical in a true sense is operated primarily by a liquid column. In other words, it is hydraulically actuated by the mass of liquid or by the hydrostatic pressure thereof except at such times when the bottle is set upright in normal position when it will gravitate to

its lowermost position engaging with the seat to form the seal.

It will be apparent from the foregoing detailed description that the device of this invention operates very largely, if not almost entirely, by the application of differential pressures in contradistinction to mere buoyancy or gravity which has so commonly dominated prior practice. Furthermore, it is of importance to remember that the sealing element 1 is operated primarily by such differential pressures which are made applicable to the element by enclosing the same within a passage exteriorly of the valve seat and adapted to direct a liquid column against the element to effect movement of the latter. The operation of the parts may therefore be said to be positive and reliable. The arrangement is moreover such that it will not readily get out of order, but will function under all conditions to 20 permit discharge of the contents of the bottle but preclude refilling thereof.

The method of this invention may be accomplished through the employment of apparatus other than that specifically described and the 25 apparatus may of course be modified through the substitution of equivalents without departing from this invention, the scope of which is to be understood as commensurate with the appended claims.

Having thus fully described the invention, what I claim as new and desire to secure by Letters Patent is:

1. In an assembly of the character described, a housing provided therein with a valve seat, a sealing member in the housing, a guide embracing the sealing member and forming therein a walled passage of a cross section corresponding to that of the sealing member with sufficient clearance between the sealing member and the 40 wall of the passage to permit of movement of the sealing member longitudinally of said passage but to preclude unrestricted flow of liquid through the clearance space thus provided, a duct arranged to by-pass the sealing member 45 when said sealing member is free from the valve seat, and a check valve cooperating with the outer terminus of said duct, and independent of said valve seat.

2. In an assembly of the character described, a housing provided therein with a valve seat, a sealing member in the housing, a guide embracing the sealing member and forming therein a walled passage of a cross section corresponding to that of the sealing member with sufficient 55 clearance between the sealing member and the wall of the passage to permit of movement of the sealing member longitudinally of said passage but to preclude unrestricted flow of liquid through the clearance space thus provided, a duct 60 arranged to by-pass the sealing member when said sealing member is free from the valve seat, and a check valve cooperating with the outer terminus of said duct, and independent of said valve seat, said sealing member being non-buoyant.

3. In an assembly of the character described, a housing provided therein with a valve seat, a sealing member in the housing, a guide embracing the sealing member and forming therein a walled passage of a cross section corresponding to that of the sealing member with sufficient 70 clearance between the sealing member and the wall of the passage to permit of movement of the sealing member longitudinally of said passage but 75 to preclude unrestricted flow of liquid through

the clearance space thus provided, a duct arranged to by-pass the sealing member when said sealing member is free from the valve seat, and a check valve cooperating with the outer terminus of said duct, and independent of said valve seat, said sealing member being non-buoyant and the check valve being buoyant.

4. In an assembly of the character described, a housing having a liquid outlet at one end and a valve seat within its other end, an elongated cylindrical walled passage positioned between the valve seat and the outlet of the housing, a circular sealing element within the passage and having sufficient clearance with respect to the wall of the passage to permit of movement of the sealing element axially of the passage in a direction toward and away from the valve seat, means for limiting the movement of the sealing member in a direction away from the valve seat, a by-pass around the sealing member when the latter is free from the seat, and a check valve cooperating with said by-pass and independent of said valve seat and arranged to permit liquid to flow in the direction of the outlet of the housing, but to preclude retrograde flow of such liquid.

5. In an assembly of the character described, a housing having a liquid outlet at one end and a valve seat within its other end, an elongated cylindrical walled passage positioned between the valve seat and the outlet of the housing, a circular sealing element within the passage and having sufficient clearance with respect to the wall of the passage to permit of movement of the sealing element axially of the passage in a direction toward and away from the valve seat, means for limiting the movement of the sealing member in a direction away from the valve seat, a by-pass around the sealing member when the latter is free from the seat, and a check valve for said duct, and independent of said valve seat, and arranged to permit liquid to flow in the direction of the outlet of the housing, but to preclude retrograde flow of such liquid, and a baffle juxtaposed with the outlet of the housing to preclude the introduction of wires and the like into the housing from the exterior thereof.

6. In an assembly of the character described, a housing provided therein with a cylinder open at both ends, a piston in said cylinder, a valve seat at one end of the cylinder against which the piston is adapted to seat and form a seal when moved in one direction, a stop at the other end of the cylinder to limit the movement of the piston away from the seat, a by-pass exteriorly of the valve seat and around said cylinder to permit liquid to flow therethrough in a direction away from the seat when the piston is removed from the seat, and a check valve associated with said by-pass and located to preclude the application of external hydrostatic pressure through the by-pass to the interior end of the piston when said check valve is closed.

7. In an assembly of the character described, a housing provided at one end with a liquid outlet and at the opposite end with a valve seat, a cylinder within the housing intermediate said seat and outlet, a piston in said cylinder constituted to form a sealing element when in engagement with the valve seat, a by-pass exteriorly of the valve seat and around the piston when the piston is free from engagement with the valve seat to permit liquid to flow through the by-pass in a direction away from the seat, and a check valve for said by-pass and located to preclude

the application of external hydrostatic pressure through the by-pass to the interior end of the piston when said check valve is closed.

8. In an assembly of the character described, a housing provided at one end with an outlet and having at its other end a yieldable apertured seat, a cylinder positioned within the housing between said seat and outlet, a piston operable in said cylinder and adapted for engagement with the apertured seat to form a seal therewith, a walled duct by-passing the piston exteriorly of said seat when the piston is free from said seat to permit liquid to flow through said by-pass duct in a direction away from the seat, and means cooperating with the by-pass to preclude the application of external hydrostatic pressure through the by-pass to the interior end of the piston when said check valve is closed.

9. In an assembly of the character described, a housing provided at one end with an outlet and at its opposite end with a seat, a cylinder within the housing between said outlet and seat, a piston operable in said cylinder and adapted for engagement with the seat to form a seal therewith, said piston being non-buoyant, a walled by-pass duct by-passing the piston when the latter is free from engagement with the seat, and a buoyant check valve adapted to cooperate with the outlet end of the by-pass duct remote from said seat to seal said duct against flow of liquid in a retrograde direction through the duct.

10. In an assembly of the character described, a housing provided at one end with an outlet and at its opposite end with a seat, a cylinder within the housing between said outlet and seat, a piston operable in said cylinder and adapted for engagement with the seat to form a seal therewith, said piston being non-buoyant, a walled by-pass duct by-passing the piston when the latter is free from engagement with the seat, a buoyant check valve adapted to cooperate with the outlet end of the by-pass duct remote from said seat to seal said duct against flow of liquid in a retrograde direction through the duct, and guide ribs formed on the interior of the housing to guide the movement of the buoyant check valve with a minimum of friction.

11. A non-refillable bottle provided with a walled outlet chamber having a valve seat at its base, a cylinder axially aligned with the valve seat and positioned within the chamber, a piston in said cylinder and of greater specific gravity than the liquid to be contained in the bottle, said piston normally engaging with the seat to form a seal therewith, but being movable by hydrostatic pressure of liquid contained in the bottle when the bottle is inverted to shift the piston from engagement with the seat, a walled duct leading from a point beyond the seat to a point beyond the outermost travel of the piston and through which liquid is adapted to flow from the bottle when the bottle is inverted and the piston retracted from the seat, and a check valve cooperating with said by-pass duct and located to preclude the application of external hydrostatic pressure through the by-pass to the interior end of the piston when said check valve is closed.

12. A non-refillable bottle provided with a walled outlet chamber having a valve seat at its base, a cylinder within said walled outlet chamber, a spherical piston operable within the cylinder and adapted upon movement in one direction to engage with the seat to form a seal therewith, said spherical piston having substantially the same diameter as the cylinder to be moved axially of the cylinder by the hydrostatic pressure of a column of liquid acting against one side of the piston to force the piston from its seat and against the opposite side of the piston to force it to its seat, a walled duct by-passing the piston beyond the valve seat when the piston is free from its seat, said walled duct having a check valve located to preclude the application of external hydrostatic pressure through the by-pass to the interior end of the piston when said check valve is closed.

13. In an assembly of the character described, a container having an outlet mouth, a housing aligned with said outlet mouth, a combined gasket and seat member having an aperture therein and interposed between the outlet mouth and housing to form a tight joint therebetween and to simultaneously function as a valve seat, a non-buoyant sphere adapted to gravitate into engagement with the aperture and form a seal therewith when the container is in upright position, a guide cage coaxial with the sphere and partially embracing the same at all times to guide the sphere for substantially rectilinear movement in a direction toward and away from the seat, means for limiting the movement of the sphere in a direction away from the seat, a walled duct by-passing the sphere when the sphere is free from its seat and through which liquid may be discharged from the container, said walled duct having a check valve, independent of said valve seat, for precluding flow of liquid through said duct into the container, and said cage being so formed that the sphere, when in engagement with the limiting means will substantially preclude the flow of liquid from the container except through the by-pass duct.

14. In an assembly of the character described, a container having an outlet passage provided with a valve seat and beyond which valve seat said outlet passage is divided into two distinct passages, one of which constitutes a guide passage for a valve and the other of which constitutes a by-pass of the valve, a non-buoyant valve in said valve passage and movable from engagement with the seat into a position removed from the seat to permit the liquid to be discharged from the container through the by-pass, said valve guide passage being shaped to form with the valve, when the latter is removed from its seat, a barrier to the flow of liquid through said passage around the valve, whereby discharge of the liquid in appreciable quantities can be accomplished only through the by-pass, there being a check valve associated with the by-pass and located to preclude the application of external hydrostatic pressure through the by-pass to the interior side of the non-buoyant valve when said check valve is closed.
